J. W. COX.

DOOR HOLDER AND WINDOW LOCK.
APPLICATION FILED DEO. 15, 1910.

1,111,996.

Patented Sept. 29, 1914.

UNITED STATES PATENT OFFICE.

JAMES W. COX, OF ASHLAND, KENTUCKY.

DOOR-HOLDER AND WINDOW-LOCK.

1,111,996.

Specification of Letters Patent. Patented Sept. 29, 1914.

Application filed December 15, 1910. Serial No. 597,503.

To all whom it may concern:

Be it known that I, JAMES W. COX, a citizen of the United States, residing at Ashland, in the county of Boyd and State of Kentucky, have invented a new and useful Door-Holder and Window-Lock, of which the following is a specification.

It is the object of this invention to provide a device adapted to hold a door or window fixedly against movement in one direction, the device permitting the door or window to have a limited movement in an opposite direction.

Another object of the invention is to provide a resilient locking member, and to provide fixed members, with one of which the locking member is pivotally connected, the other of said fixed members being adapted for adjustable connection with the locking member.

The invention resides in the combination and arrangement of parts and in the details of construction hereinafter described and claimed, it being understood that changes in the precise embodiment of invention herein disclosed can be made within the scope of what is claimed without departing from the spirit of the invention.

In the drawings,—

Figure 1 shows the invention in perspective; Fig. 2 is a perspective showing the device applied to the sashes of a window; and Fig. 3 is a perspective showing the device applied as a door-holding means.

In carrying out the invention there is provided a fixed member 1, including rectangularly disposed flanges 2 and 3, the flange 2 being provided with spaced openings 4, adapted to receive securing elements, wherefore the fixed member 1 is held in place rigidly upon a supporting structure.

The invention further includes another fixed member 5, comprising angularly disposed flanges 6 and 7, the member 5 being of considerable length, while the member 1 is relatively short. In the flange 7 of the member 5, there is an elongated slot 8, one wall of which is defined by the flange 6. Located in the flange 7, and positioned between the slot 8 and the outer edge 9 of the flange, are a series of openings 10, disposed substantially parallel with the slot 8.

A locking member, denoted generally by the numeral 11, is seen in clearest detail in Fig. 1. This locking member 11 is fashioned from a rod of metal bent upon itself

to form an eye 12 adapted to be engaged in an opening in the outstanding flange 3 of the fixed member 1. At its other end, the locking member is bent to form a rectangularly disposed finger 14, adapted to engage successively in the openings 10 of the flange 7 of the fixed member 5. Intermediate its ends, the rod which forms the locking member, is bent upon itself to fashion a closely coiled helical spring 15, responsive to traction only.

The device as above described, may be used in a variety of ways. For instance, as shown in Fig. 2, the fixed member 1 may be secured to the upper cross rail 16 of a lower window sash, the fixed member 5 being secured in upright relation to one of the stiles 17 of the upper sash of the window. In such instance, the finger 14 of the locking member may be engaged successively in the openings 10, permitting the upper sash to be disposed in open position, or if the upper sash is held fixed, the lower sash may be maintained in open positions of different extents, depending upon which of the openings 10 is engaged by the finger 14 of the locking member.

If desired, as shown in Fig. 3, the fixed member 1 may be secured to the jamb 18 of a doorway, the fixed member 5 being attached to the door 19, transversely of the same. When the device is positioned as shown in Fig. 3, the finger 14 may be engaged successively in the openings 10, thus permitting the door 19 to be positioned at different angles.

Referring to Fig. 2, it will be seen that since the spring 15 is closely coiled, the upper sash cannot be pushed downwardly, nor can the lower sash be pushed upwardly. However, since the spring 15 is responsive to tensile strain, the open sash may be slid into closed position, without disengaging the finger 14 from the fixed member 5.

Referring to Fig. 3, it will be seen that the spring 15 will elongate, to permit the door 19 to be swung into closed position, without permitting the door to be swung into a more widely opened position.

When it is desired to raise or lower the sashes to a limited extent, without putting the spring 15 under tension, the finger 14 may be placed in the slot 8, for reciprocation therein, the locking member being thus held against assuming a conspicuous, depending position upon the lower sash. Likewise, re-

ferring to Fig. 3, it will be seen that when the finger 14 reciprocates in the slot 8, the door may be opened and closed, without putting the spring 15 under tension, the locking member, however, being held in the horizontally disposed position shown in Fig. 3.

It is to be noted, referring to Figs. 2 and 3, that when the finger 14 reciprocates in the slot 8, the finger will slide in contact with the flange 6, owing to the fact that the flange 6 defines one wall in the slot 8. By this construction, the stile 17 of the window sash, in the one instance, and the door 19 in the other instance, will not be marred by the reciprocation of the finger, the flange 6 constituting a guard for the structure upon which the fixed member 5 is mounted.

Having thus described the invention, what is claimed is:—

- 20 1. A device for locking a barrier in a partially opened position and for restraining the barrier against further opening, but permitting the barrier to be moved to a completely closed position, the device comprising a rod in a single length coiled upon itself intermediate its ends to form a spring

the convolutions of which are in contact to render the spring responsive to traction only and to render the rod effective as a rigid prop constituting the sole means for limiting 30 the opening of the barrier; means for supporting one end of the rod pivotally but against longitudinal movement; and a support-engaging member having an elongated slot and provided with an opening, the rod 35 having a finger adapted to slide in the slot and to register against sliding in the opening.

2. In a device of the class described, the combination with a fixed support and a movable barrier, of a longitudinally resilient one-piece prop connecting the support and the barrier, the prop having a fixed minimum length under compression and having a variable length under elongation. 40

In testimony that I claim the foregoing as my own, I have hereto affixed my signature in the presence of two witnesses.

JAMES W. COX.
